ABSTRACT

A device for transporting thermal energy at temperatures lying below the λ -temperature of helium between a cooled ^{4} He container having a temperature lower than that of the λ -point and a place to be cooled or a further container; the device comprises a pipe which has one end in communication with said container and the other end which is brought in thermal contact with the article to be cooled or debouches in the further container, the pipe comprising a sintered superleak which extends throughout the length of the pipe and covers a part of the cross-section thereof.

DEVICE FOR TRANSPORTING THERMAL ENERGY AT TEMPERATURE LYING BELOW THE λ -TEMPERATURE OF HELIUM

BACKGROUND OF THE INVENTION

The invention relates to a device for transporting thermal energy at temperatures lying below the λ -temperature of helium between a cooled ^4He container having a temperature lower than that of the λ -point and a place to be cooled or a further container; the device comprises a pipe which has one end in communication with said container and the other end of which can be brought in thermal contact with the object to be cooled or debouches in the further container.

It is known that ^4He at temperatures below the λ -point has a thermal conductivity which is very much ($1,000 \times$) larger than that of solids. This property can be related to the fact that ^4He at these temperatures consists in part of normal fluid which is viscous and has a given entropy, while the other part is a superfluid which has no viscosity and an entropy zero. When thermal energy is supplied to one end of the pipe by the object to be cooled, a temperature difference ΔT occurs across said pipe in which a thermal transport starts occurring in that superfluid starts flowing toward the warmer end, while normal fluid flows in the opposite direction, and that in such manner that the overall mass transport is zero. It has been found that the so-called reciprocal friction of the flow of superfluid and the oppositely directed flow of normal fluid, particularly in the case of a larger supply of thermal energy, has a very adverse influence on the quantity of thermal energy which can be transported.

SUMMARY OF THE NEW INVENTION

It is the object of the invention to provide a device of the type to which the present invention relates and which has a better power of transporting thermal energy than the so far known devices.

In order to achieve this objective the device according to the invention is characterized in that the pipe comprises a sintered superleak which extends throughout the length of the pipe and covers a part of the cross-section of the pipe.

Within the scope of the present application, a superleak is to be understood to mean a mass of material of such a high density that normal fluid cannot pass through said mass and superfluid can pass through said mass without turbulence in the fluid.

If in the device according to the invention, a temperature difference ΔT is applied across the pipe, the superfluid will flow through the superleak to the place of higher temperature, while the normal fluid will flow in the opposite direction through the remainder of the tube. The so-called reciprocal friction between the two flows does not occur, which results in a considerably better thermal conductivity and hence in a lower temperature difference ΔT with the same thermal flow.

In a further favorable embodiment the superleak covers the

whole inner wall of the pipe. The advantage of this is that the superleak also counteracts penetration of thermal energy from without.

5 BRIEF DESCRIPTION OF THE DRAWING

In order that the invention may be readily carried into effect, it will now be described in greater detail, by way of example, with reference to the accompanying drawing showing an embodiment of a device for transporting thermal energy and consisting of a pipe with ^4He and provided with a superleak.

DESCRIPTION OF THE PREFERRED EMBODIMENT

Reference numeral 1 denotes a container filled with liquid ^4He at a temperature lower than that of the λ -point. pipe 2 communicates with the said container and communicates at its other end 3 in a heat conducting manner with an object 4 to be cooled. The inner wall of the pipe 2 is covered with a superleak 5 of, for example, sintered aluminum oxide particles or silicon carbide particles. Such a superleak has the property that normal fluid cannot pass through it, while superfluid flows through such a superleak without turbulence occurring. When thermal energy is supplied to the end of the tube 3 by the article 4, a certain temperature difference occurs across the pipe 2. The superfluid will start flowing to the end 3 of the pipe while an equally large mass flow of normal fluid will flow to container 1. The superfluid will flow through the superleak 5 without turbulence, so that the flow of normal fluid is not impeded. In this manner, a particularly large amount of thermal energy can be transported through pipe 2, with a small temperature difference across the pipe.

Providing the superleak against the inner wall of the tube 2 has the advantage that the superleak counteracts inleak of thermal energy but, if desirable, the superleak may also be arranged detached from the wall of the pipe.

Instead of bringing the end 3 of the pipe in thermal contact with an object to be cooled, the pipe may also be made to communicate with a further container which, for example, serves as a storage container from which liquid can be drained or which is in thermal contact with a number of objects to be cooled.

What is claimed is:

1. A device for transporting thermal energy at temperatures lying below the λ -temperature of helium, between a container of cooled ^4He having a temperature lower than that of the λ -point and an object to be cooled, the device comprising a pipe which has one end in communication with said container, and the other end which can be brought into thermal contact with the object to be cooled, characterized in that said pipe comprises a sintered superleak which extends along the length of said pipe and extends across only a part of the cross-section thereof.

2. A device as claimed in claim 1, characterized in that the superleak covers the whole inner wall surface of the pipe.
